UNITED STATES PATENT OFFICE

WILLIAM P. STUNZ, OF LANSDOWNE, MARYLAND, ASSIGNOR TO SAFE DEPOSIT AND TRUST COMPANY OF BALTIMORE, A CORPORATION OF MARYLAND, AS TRUSTEE UNDER THE WILL OF GEORGE R. WEBB

MULTIPLEX TRANSMITTER

Application filed January 6, 1928. Serial No. 244,930.

My invention relates to telephonic transmitters, and more particularly to such instruments for transmission of sound vibrations, especially of the character of musical vibrations as taken from a record. One object of the present invention is to increase the capacity of the output of the electrical current generating elements of the transmitter so that the volume of vibrations emitted from a receiver will be materially increased without distortion that would impair the clearness of delivery of the received vibrations and whereby the instrument has the capacity to fill or supply an auditorium chamber of larger area with the musical or sound vibrations with greater clearness or distinctness than previously.

It has also for another object to eliminate entirely or to a material extent the objectionable and disconcerting metallic or "scratchy" noises resulting from contact of the tracer element or needle with the material or substance of the record from which the musical or other vibrations are received and transmitted.

It has also for other objects to provide improved features in various parts of the transmitter unit whereby material advantages are gained as will be hereinafter made to appear.

To the accomplishment of the foregoing, the invention consists in the features herein-after particularly described and then sought to be clearly defined by the claims, reference being had to the accompanying drawings forming a part hereof, and in which

Figure 1 is a side elevation, with front and rear cover plates removed;

Figure 2 is a sectional plan, taken on line 2-2 of Fig. 1;

Figure 3 is a cross-section, on line 3-3 of Fig. 2;

Figure 4 is a similar view on line 4-4 of Fig. 2;

Figure 5 is a sectional view on line 5-5 of Fig. 3;

Figure 6 is a detail view, showing the spider and vibrating arm, or lever;

Figure 7 is a detail perspective diagrammatical view, showing the direction of the electrical circuits;

Figure 8 is an enlarged vertical section, taken on line 8-8 of Fig. 1;

Figure 9 is a detail perspective view of flat fulcrum spring;

Figure 10 is a detail view, showing a modification of the fulcrum spring;

Figure 11 is a sectional view taken on line 11-11 of Fig. 10;

Figure 12 is a diagrammatic view, showing a Wheatstone bridge circuit with eight granular-carbon chambers.

In the drawings, the letter A designates in general the electrical current or circuit creating unit; B the record tracer or reproducing needle unit; C the arm which connects the reproducing needle unit with the electrical current or circuit unit; and D the member by which the units A, B, and C, are sustained from a suitable support and which permits a vertical as well as a horizontal movement of the units A, B, and C to conform to the impressed recorded undulations of the record and to any surface irregularities in the plane of the record.

The unit A comprises a casing formed of end plates 1, preferably brass, and intermediate member 2, preferably brass, connecting the end plates. Within the casing are two bridge plates 3, preferably of brass, secured in position by rods 4, to which the plates are connected, passing through the end plates 1 and provided with spacing sleeves 5.

Within the casing or shell there is contained a plurality of granular-carbon chambers or cups, eight of such chambers being illustrated, and designated respectively by the numerals 7 to 14. One set, consisting of four of the chambers 7, 8, 9 and 10, is supported from a plate or block 15, formed preferably of bakelite, or other suitable insulating material, and the other set consisting of chambers 11, 12, 13 and 14 supported from a similarly formed plate or block 16. The chambers are disposed so that one set of four will face the other set of four, as illustrated.

Each chamber is made up of a base-member 17, of a suitable electrical conductor material, preferably brass, which has a threaded stem 18 passing through the plate and se-

cured by a nut 19; a stationary electrode 20, which may be a carbon-button, attached by a screw 22, or otherwise, to the inner face of the base-member 17; a movable electrode 23, 5 which may be a carbon-button; a granular carbon containing space or chamber 24 between the fixed and movable electrodes, and an enclosing wall 25, say of felt. The back and front blocks 15 and 16 carrying the 10 granular carbon chambers or cells are tied together by the metal posts 26, 27, 28 and 29. Between the bridge-plates 3 and the plates or blocks 15 and 16, respectively, from which the granular carbon cells or electrodes are 15 supported, there are placed cushioning pads 30 of soft rubber which relieve to a greater or less extent disturbance of the carbon granules from movements of the supporting parts of the transmitter. Between the insulated plates or blocks 15, 16 and the base-members of the several granular carbon cells there are placed electrical conductor-plates 31, 32, 33 and 34, the two sets of connector-plates having substantially the outline illustrated and one pair of plates of each set having 20 its plates joined by a connecting neck 35.

In the space between the two sets of granular carbon cells, four cells to each set, there is positioned an oscillatory spider E, preferably made of aluminum, having four radial arms 36, 37, 38 and 39. This spider is supported to oscillate by the adjustable threaded pivot pins 40 threaded in bearings 41 attached to the face of plate or block 16. The 30 spider carries two sets of movable electrodes 23, say carbon-buttons, four electrodes to each set, corresponding to the two sets of granular carbon cells, four cells to each set of electrodes (four in number) lying opposite one face of the spider and the other set (four in number) opposite the other face, the electrodes being carried by the arms of the spider and suitably connected thereto, say by the screws 43, insulated therefrom and 35 from spacing washers 44 by an insulating bushing 45 and mica washers 47. The two upper movable electrodes of each set will be connected with the companion two lower electrodes by thin metal conductor strips 46 40 which will be insulated from the spider arms by mica washers 47.

By the employment of the oscillatory spider having a set of four granular carbon cells on one side and four cells on the other side, the granular carbon in two of the cells on one side is compressed and the carbon in two cells on the other side is likewise compressed while the carbon of the other cells, two on each side, is released from compression, so that there will be sent out to the receiver or loud speaker an increased volume of current from the cells whose granular carbon is under compression, the discharge of the current to the loud speaker or receiver alternately changing from positive to negative, 50

being an undulatory alternating current of increased volume and resulting in a clearer reproduction of sound vibrations throughout a larger area of the receiving auditorium.

The sound vibrations thus transmitted are received from a record through the following instrumentalities. The numeral 48 designates a lever, suitably connected at one end to the oscillatory spider E and having connected to its other end a tracer or reproducing needle 49 by a resilient strip 50 connected to the end of the lever and having elastic washers 51 on each side where connected to the lever. The tracer 49 is attached to a member 52, to which the resilient strip 50 is connected, and supported on a light spring-metal member 53 attached, say by screws 54, to an inertia member 55 which may be supported by a tubular arm 56 projecting from the unit A which carries the granular carbon cells and the several movable electrodes. The inertia member 55 owing to its mass cannot respond to a high rate of vibration and hence provides or functions as a relatively fixed point for the fulcrum of the vibrating member 52 that carries the tracer 49 which sensitively responds to the vibrations derived from the record.

The annoying scratch more or less observable in reproducing vibrations from a record are due in an objectionable degree to the initial vibrations received by the tracer needle from the record and that if provision is made for absorbing these initial vibrations until they are eliminated or overcome or dissipated by the greater volume of reproduced vibrations in the rotation of the record they will be practically prevented from being noticed in transmission of the reproduced vibrations so that the final distribution of the vibrations will be clearer and free from the initial scratchy reproduction. This desired result is effected by providing for the tracer needle a variable fulcrum which provides for taking care of these initial vibrations so that only the greater dominating vibrations produced from the record are transmitted to the receiver or loud speaker. This, in the preferred form of the invention, is accomplished by providing the resilient fulcrum member 53, which in the preferred embodiment consists of a relatively thin spring plate 53 to which the member 52 carrying the tracer needle 49 is attached, say by rivets 57 so that by movement of the member 52, a torsion is set up in the spring plate 53 sufficient to absorb the initial scratch vibrations and results in only the excess or dominating vibrations being transmitted through the lever 48 to the oscillatory spider and carbon cells of the transmitter unit A and thence to line. The best results of this feature are obtained by placing or setting the broadside of the resilient fulcrum member 53, as distinguished from its edge, towards or facing the side vibratory movements of the tracer needle.

For adjusting or regulating the extent of movement of the supporting plate 53, or damping its movement, elastic faced fulcrum bearing dampers 60 are disposed on opposite 5 sides of the member 52 as clearly illustrated in Fig. 8 of the drawings, the stem of each damper having threaded engagement with a face plate 61 to the inertia member 55 and held to their adjustments by nuts 62; and 10 elastic faced dampers 63 may be positioned against opposite edges of the resilient strip 50 adjacent to its connection with the lever 48, as shown in Fig. 8 so as to give firmness to the strip in its vibrations, the dampers being 15 adjustable and held by nuts 64 as illustrated.

A modified form of torsional spring fulcrum for the tracer needle 49 is illustrated in Figs. 10 and 11 of the drawings. In this modification, the spring-plate support is indicated by the numeral 65 and is set with its edges towards or facing the direction of side movement of the tracer needle and is attached by screws 66 to the inertia element 55. To give greater resiliency to the spring support- 20 plate of this modification, the plate is formed with cut-out portions 67 which permit the spring fulcrum to yield under torsional strains imparted to the fulcrum under vibrations of the tracer needle, with the view 25 of taking up the initial scratch vibrations previously mentioned. This form of fulcrum to which the needle carrying element 52 is connected gives good results but the 30 form of torsional spring fulcrum first described is regarded as the better form. It is preferred, but not essential, to provide a 35 felt ring 68 interposed between one of the face-plates 61 of the inertia element 55 and an annulus extension 69 of the tubular arm 40 56 as shown in Fig. 2 of the drawings.

It will be observed from reading of Fig. 7 of the drawings, that the transmitters, or cells thereof, are included in a Wheatstone bridge circuit, and that one branch of the 45 circuit includes a plurality of more than two transmitters in the branch, in two of which transmitters the granular carbon is under compression, or has relatively low resistance, while in the other branch of the circuit are 50 a plurality of more than two transmitters or granular carbon cells, in two of which the granular carbon is under reduced compression, or has relatively high resistance simultaneously with the greater compression or 55 relatively low resistance of the granular carbon of the companion cells in the other branch, thereby resulting in sending to line the output of two transmitters in the same branch at the same time so that there is a 60 multiplied output of current from the branch. It will also be observed that the plurality of transmitters or granular carbon cells in each branch act in pairs for compressing or reducing the resistance in multiple transmitters or 65 cells of one branch of the circuit while simul-

taneously reducing the compression, or increasing the resistance in a plurality of transmitters or granular carbon cells of the other branch of the circuit, and that the plurality of companion cells in each branch of the circuit act in alternation to the companion plurality of transmitters or cells of the other branch whereby the output of current from one branch is supplemented by the output from the other branch, thereby giving a 70 greater output of current to line and proportionately increasing the result sought. In Fig. 7 of the drawings, the single headed arrows indicate the circuit in one branch established when two cells have the granular carbon compressed to decrease the resistance and two cells have the carbon released to increase the resistance; and the double headed arrows indicate the circuit established simultaneously in the other branch when the spider is oscillated in one direction. The opposite 75 conditions apply or exist when the spider is oscillated in the opposite direction, as will be obvious to the skilled in the art, aided by the illustrations given. Otherwise stated, when the spider carrying the movable electrodes is in normal position, the granular carbon of the transmitter cells at opposite faces of the spider have the same state or 80 condition of resistance, and upon oscillation of the spider the carbon in two cells at one face thereof is placed under compression while in the companion cells at the same face of the spider the compression on the granular carbon therein is lessened, and at the same 85 time the carbon in two cells on the opposite side face of the spider, for instance the two cells back of the other cells in which the carbon is being compressed, have their carbon 90 under a reduced pressure, and the two companion cells on the same side, which lie back of the two cells on the other face which are under reduced pressure, have their carbon placed under compression. This results in two carbon cells at one face of the spider having low 95 resistance given thereto and the other two having high resistance imparted to them while the cells at the opposite face have high 100 resistance imparted to two of them and low resistance to the other two, and this takes 105 place in alternation under oscillating cycles of the spider and results in an increased output of alternating undulatory current, changing 110 from positive to negative, being sent to line in the cycle of oscillations of the spider. The advantage of the connector plates 31, 32, 33 and 34 and the connector strips 46 is to dispense with the necessity of supplying a 115 multiplicity of connector wires leading to and from the plurality of granular carbon cells embodied in transmitter unit A. The advantage of providing the torsional spring fulcrum for the tracer needle has been sufficiently explained without repetition.

The unit member A has an arm 69' ex- 120 125 130

tending from one of the end-plates 1 by which the unit is pivotally supported from a post 70 which has a reduced end 71 so as to fit in a bracket or other support (not shown) 5 whereby the unit A and associated parts is capable of being swung laterally and also in a vertical plane to conform to the side movements of the tracer needle and to provide for surface irregularities in the plane 10 of the record.

While I have illustrated and described with particularity the preferred details of the several parts and their relative relationship, it is to be understood that changes may 15 be made therein, and essential features as sought to be defined by the appended claims may be retained.

Having described my invention and set forth its merits, what I claim is:—

20 1. A telephone instrument including an oscillating member, a plurality of individual transmitters and their electrodes responsive to received vibrations, a plurality of the transmitters being placed on each side of 25 the oscillating member, a Wheatstone circuit inclusive of the transmitters and in which the transmitters are disposed so that a plural number in one branch of the circuit will be placed under high resistance and a corresponding 30 number in another branch will be simultaneously placed under a reduced resistance, in alternation between the respective branches, whereby an increased output of 35 current to line, alternating between negative and positive currents, will be effective.

2. A telephone instrument including an oscillating member, a plurality of eight individual transmitters and their electrodes responsive to received vibrations, a plurality 40 of the transmitters being placed on each side of the oscillating member, a circuit inclusive of the transmitters and in which the transmitters are disposed with four in one branch of the circuit and four in another branch and 45 arranged so that a plural number of the transmitters in one branch will be under high resistance and a corresponding number in the other branch will be simultaneously under a reduced resistance, the transmitters 50 in one branch alternating in change of resistance from high to low with the transmitters of the other branch, whereby an increased output of current to line, alternating between negative and positive, will be effected.

55 3. A telephone instrument comprising a plurality of transmitters and their electrodes responsive to received vibrations, an oscillatory member having sets of transmitters, including four in each set, disposed at opposite faces of said member and operatively connected therewith, a Wheatstone circuit in which the transmitters are included, and means for oscillating said member to increase the resistance in a plurality of the transmitters disposed at one face of the member and

reduced resistance in a plurality of the transmitters at the opposite face of said member, in alternation, whereby an increased output of current to line, alternating between negative and positive current, is effected.

In testimony whereof I affix my signature.

WILLIAM P. STUNZ.
